UNITED STATES PATENT OFFICE.

DAVID PATON, OF NEW YORK, N. Y., ASSIGNOR TO JOSEPH WILD & CO.,
OF SAME PLACE.

DESIGN FOR A CARPET-PATTERN.

Specification forming part of Design No. 5,555, dated February 20, 1872.

Specification describing a new and original Design for Carpet, invented by DAVID PATON, of New York city, in the county and State of New York.

The photograph represents my new design. The same consists in a peculiar new manner of ornamenting the border of the center-piece A by a wreath, B, of flowers, so wound around

said border as to be alternately exposed to view and partly concealed.

I claim as my invention—

The design for a center-piece, having the twining wreath around the border, as specified.

Witnesses: DAVID PATON.

GEO. W. MABEE,

T. B. MOSHER.
